UNITED STATES PATENT OFFICE.

ALFRED AHLFORS, OF ESLÖF, SWEDEN.

ORGAN FOR REINFORCING MELODY TONES.

SPECIFICATION forming part of Letters Patent No. 624,721, dated May 9, 1899.

Application filed September 17, 1898. Serial No. 691,234. (No model.)

To all whom it may concern:

Be it known that I, ALFRED AHLFORS, manufacturer, a subject of the King of Sweden and Norway, residing in Eslöf, Sweden, have invented certain new and useful Improvements in Organs for the Purpose of Reinforcing Melody Tones; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The purpose of this invention is an improvement in organs to provide means for rendering the melody more prominent, which is especially desirable in playing preludes, chorals, and the like.

20 Figure 1 shows a vertical section, Fig. 2 a longitudinal section, and Fig. 3 details, of my improved device.

Similar letters of reference refer to like parts throughout the several views.

25 Each note is sounded by a pair of reeds *b* and *b'*, having the same pitch, which reeds are inclosed in their respective boxes or cavities *L* and *L'* and are sounded by depressing a common pallet *K* by the key *a* and corresponding plunger *X*. From the arrangement shown in the drawings, Fig. 1, it will be seen that each note is sounded by two reeds, and in order to make the melody more prominent I have devised means whereby a reed of all 30 the pairs of reeds may be muted except those playing the melody, thus giving the tones of the melody notes their full value. Across one set of reed-boxes I place a rail *C'*, from which are supported the valves *B* for closing 35 the reed-cavities. To the rail *C'* above each box I have shown secured brackets *C*, in which are pivoted the weighted valves *B* for closing the reed-cavities and the weighted levers *A*, which operate said valves. These 40 levers are provided with weights *H* to hold them in normal position and carry on their forward arms bridle-wires *D*, to which the swinging or hinged valves *B* are connected by the bridles *E*. These bridle-wires *D* are not 45 fastened in the levers *A*, so as to control the valve just below, but are inclined toward the side so as to project over the valve controlling the next adjoining reed-cavity, so that when

the lever *A* is actuated that reed over which it is situated is not muted, but instead the 55 next adjoining one, (preferably to the left.)

Upon one end of each lever *A*, I provide a tap or projecting pin *F* for the purpose of depressing the next adjoining lever, (preferably to the left,) so that when a note is sounded 60 the reeds of all the other notes damped by valves *B* (say to the left) are muted.

Each key carries a contact-piece *G*, that operates the lever *A* by having contact either directly with the end of said lever or with a 65 wear-plate thereon, as shown.

The operation of the device is as follows: The key *a* is depressed, the plunger *X* opens the pallet *K* to the reed-cavities, and simultaneously the contact-piece *G* depresses the 70 lever *A*, which causes the end of the bridle-wire *D* to approach the reed-cavity, slacken the bridle, and allow the valve *B*, which is hinged to the next adjoining reed-cavity on the left, to drop on its seat and mute the reed, 75 and at the same time that the lever *A* is depressed the pin *F*, that projects over the next adjoining lever *A*, will impinge upon said lever and depress it also, which lever will likewise depress its neighbor, and so on, so 80 that all the valves (say to the left of the note sounded) are closed, the reeds muted, and only the upper or melody note given full quality.

It is obvious that by means of a common register, operated by the knee or otherwise, all 85 the valves *B* may be held closed, whereby the mechanism described is put into or out of operation.

Having thus described my invention, what I claim as new therein, and desire to secure 90 by Letters Patent, is—

In an organ, two reed-boxes for each note, a mute for one of each pair of reed-cavities, comprising a clack-valve, a weighted key-operated lever, a bridle-wire in one arm of said lever, and a flexible detent from said wire to said valve of one of the adjoining pair of reed-cavities, substantially as and for the purpose set forth.

In testimony that I claim the foregoing as 100 my invention I have signed my name in presence of two subscribing witnesses.

ALFR. AHLFORS.
